WILLIAM PAIN, OF LITTLE ROCK, WASHINGTON, ASSIGNOR OF ONE-THIRD TO DOMINIC BOPO, OF SEATTLE, WASHINGTON, AND ONE-THIRD TO JULIA E. WALDRIP, OF OLYMPIA, WASHINGTON.

RIBBON-INKING ATTACHMENT FOR TYPEWRITERS.

1,387,980.

Specification of Letters Patent. Patented Apr. 20, 1920.

Application filed June 12, 1919. Serial No. 303,722.

To all whom it may concern:

Be it known that I, WILLIAM PAIN, a citizen of the United States, residing at Little Rock, in the county of Thurston and State 5 of Washington, have invented certain new and useful Improvements in Ribbon-Inking Attachments for Typewriters, of which the following is a specification.

This invention relates to ribbon-inking 10 devices for typewriting machines; and its object is to produce an efficient device of this character which will be of simple and inexpensive construction, and one which may be readily applied, and will operate 15 automatically.

To these ends, the invention consists in the novel construction, adaptation and combination of parts as will be hereinafter described and claimed.

20 In the accompanying drawings, Figure 1 is a plan view of my improved ribbon-inker and showing such parts of a typewriting machine as necessary to illustrate the application of the invention. Fig. 2 is a sectional view through 2—2 of Fig. 1. Fig. 3 is a perspective view of the casing.

25 Referring to the drawings, the reference numeral 5 designates part of the machine frame of a typewriter; 6 is the platen; 7 a ribbon-guide one at each side of the frame for directing the ribbon R to and from the spools, such as 8, whereby the ribbon is given a progressive feed movement transversely of the machine.

30 As shown, the ribbon-guide 7 is formed with a straight body portion 9 having adjacent to one end a looped portion 10 which serves to direct the ribbon and extending from each side of said looped portion are 35 wing guide elements 11.

The aforescribed parts are similar to devices now employed on standard makes of typewriters—as, for example, that known as Remington.

40 In carrying out my invention, I provide a receptacle 12 for a liquid absorbent material 13—such as sponge—which is detachably connected to the ribbon-guide and is arranged to supply ink to the ribbon.

45 Said receptacle is formed with side walls 14, a back wall 15, and a bottom 16 which slopes upwardly at the front, as at 16', to within a short distance of a plane extending through the upper edges of said side walls,

so as to afford an opening, or mouth 17, below the cover plate 18. This cover plate is made removable and, by preference, is slideable in guide slots 19 provided in the side walls.

The side walls 14 are, moreover, extended 60 beyond the front edge of the bottom part 16 and are turned inwardly as shown to furnish hook-shaped fingers 20 at opposite sides of the mouth 17 of said receptacle to engage the latter to the looped portion 10 65 of said ribbon-guide. 21 represent grooves provided in the casing bottom to accommodate the guide elements 11 which thereby coöperate with the fingers 20 to prevent any lateral displacement of the casing when in 70 use.

The absorbent material or sponge 13 is placed within the casing and saturated with ink, preferably before the cover plate is moved into its closed position, and may be 75 replenished as required by introducing ink through an aperture 23 provided in the cover plate.

In operation, the ribbon in passing over the ribbon-guide 7 is caused to travel between the looped portion 10 thereof and a portion of the sponge which protrudes from the mouth of the casing, said looped portion of the ribbon guide serving to retain the ribbon against the sponge, so that ink 85 will be spread uniformly upon the ribbon.

Among the advantages of the invention are, first, its efficiency in inking ribbons without the necessity of removing the same from a machine and enabling their being 90 continuously used for a long time or until worn out; second, in the provision of a sponge receptacle which is substantially dust proof to exclude dirt from the ink; and third, in the provision of a ribbon inking device which need not be manipulated by the operator of a machine and thereby obviates getting her hands ink soiled.

95 What I claim, is—

1. The combination with a typewriter 100 having a ribbon and a ribbon guide connected to the typewriter, of a casing provided at one end with means for engaging said ribbon guide for securing the casing to the typewriter, said casing being provided 105 with an opening at one end thereof and at the opposite side of the ribbon from the ribbon guide, and a liquid absorbent material

provided within the casing and extending through said opening into juxtaposition with the ribbon.

2. The combination with a typewriter
5 having a ribbon and a guide therefor, of a
liquid absorbent material, and a casing serv-
ing as a receptacle for said material and
having a slot at one end through which
10 said material extends, said casing being pro-
vided with fingers at opposite sides of said

slot to engage the ribbon guide for securing
the casing thereto in position to cause the
ribbon to pass between said guide and the
material which protrudes from the casing.

Signed at Seattle, Washington, this 2nd ¹⁵
day of June, 1919.

WILLIAM PAIN.
